PULP EVAPORATOR

Everett H. Bickley, Bala-Cynwyd, Pa.

Application April 12, 1946, Serial No. 661,623

2 Claims. (Cl. 159—17)

1

The present invention relates to evaporators and more particularly to an apparatus for concentrating tomato pulp.

Heretofore the usual and common method of boiling down tomato liquid to produce 2/1 tomato pulp consists of heating the tomato liquid by means of live steam coils immersed in the liquid. The top of the kettle is open and huge clouds of steam roll out filling the room to such an extent that large fans must be operated to carry it away. Every pound of water evaporated from the tomato liquid turns into 30 cubic feet of steam, and 3000 to 4000 pounds of water are evaporated from a single kettle in 25 minutes.

The steam entrains also corrosive vapors or droplets which attack the steelwork in the penthouse. It carries away also flavors which may be of value if they could be retained.

Each pound of steam condensed in the coils gives up 880.6 B. t. u. to form water and in cooling down to the temperature of the trap discharge liberates about 102 additional heat units. This is 982.6 B. t. u. The fluids evaporated from the tomato liquid require about 970 B. t. u. per pound, plus about 145 B. t. u. per pound to heat it up to the boiling point. This is a total of 1115 B. t. u. Allowing for recondensation, radiation, heat losses and specific heat of the containers (9%) it would require about 1.04 pounds of steam to remove 1 pound of tomato liquid. It is obvious that one kettle will take about 100 boiler horse power to keep it going, or about 50 cubic feet of steam per second will be rolling out of the kettle.

Some of the objects of the present invention are: to provide an improved apparatus for boiling down tomato liquid to produce tomato pulp; to provide a new and novel apparatus for evaporating tomato fluid; to provide an apparatus for evaporating tomato liquid wherein corrosive vapors are prevented from escaping and in consequence there is no loss of flavor; to provide an evaporator for tomato fluid wherein the amount of steam required to convert one pound of tomato liquid is materially reduced; to provide an evaporating system applicable either to batch or continuous evaporation, both with a minimum of recondensation, radiation, and heat losses; to provide a novel closed system of tomato fluid evaporation, and to provide other improvements as will hereinafter appear.

Referring to the drawings, Fig. 1 represents diagrammatically a side elevation partly broken away of an evaporator embodying one form of the present invention; Fig. 2 represents diagram-

atically a side elevation of a modified form of the invention; and Fig. 3 represents a sectional detail of the three way valve and associated parts.

5 Referring to Fig. 1 of the drawings, one form of apparatus of the invention is shown for concentrating vegetable pulp in a batch operation, the apparatus being here illustratively described as applied to tomato pulp for use in the manufacture of ketchup, sauces and the like.

The tomato fluid to be reduced to pulp is placed in a cooking vessel 10, of the open top type having a sealing closure 11 arranged to be clamped in place by suitable hold-down clamps 12, while the bottom is, preferably, funnelled to a drain pipe 13 provided with a shut-off valve 14. A safety valve 15 may be provided in the closure 11 or other location as will be understood.

In order to preheat the tomato fluid, a heating coil 16 is mounted within the kettle 10 with its lower end passing through the kettle wall to communicate with a trap and air vent 17 located in a drain pipe 18. The upper end of the coil 15 also passes through the kettle wall to communicate with a steam supply pipe 20 leading to a source of steam supplied by a pipe 21. A control valve 22 is located in the pipe 20 in order to shut off the steam to the kettle at the proper time as will later be described.

20 For the purpose of utilizing the vapor rising from the tomato fluid while boiling, a centrifugal pump 23 is provided having its inlet connected by a pipe 24 for communication with the space in the vessel 10 above the fluid level, and its discharge connected through a T-fitting 25 with the pipe 29. This latter connection is made between the valve 22 and the kettle 10. A pressure gage 26 may be included in the pump inlet pipe 24. A steam turbine 27, preferably of the DeLaval type is arranged to drive the pump 23 and is supplied with steam from the supply pipe 21 through a control valve 28.

25 In operation the valve 28 is initially closed and the valve 22 is opened so that steam is supplied directly to the coil 16 until the fluid reaches the boiling point. At this point the valve 22 is closed and the valve 28 is opened to start the pump 23. The action of the pump 23 is to draw the vapor from the vessel 10 and compress it to a higher pressure as delivered to the coil 16, thus causing the heat to flow into the tomato fluid to continue the boiling and give off more vapors. The vapors in the coil 16 will condense and be drawn off by the trap 17. In this way the fluids 30 will be extracted from the tomato fluid until the

latter becomes tomato pulp. When this stage is reached the pump 23 is stopped and the pulp drawn off by opening the valve 14 in the drain pipe 13.

In the foregoing batch operation the starting temperature of the tomato liquid is approximately 170° F., since the tomato liquid has just been scalded. The vapors go into the pump in a saturated condition, atmospheric pressure or a little higher. The vapors come out of the pump superheated due to the compressing action of the pump. These vapors go into the coil 16 where they give up heat to the tomato liquid, causing it to boil vigorously. When the vapors have cooled down to near the temperature of the liquid, condensation takes place and the condensate is trapped out of the system. Heretofore a ton of coal was required to process 103 bushels of tomatoes, while with the apparatus of this invention one ton of coal should process 340 bushels of tomatoes or more.

Referring to Figure 2 of the drawings a modified form of the invention is for continuous operation wherein a conveyor 39 delivers the tomatoes to a decorticator and scalding 31 arranged to discharge the resultant tomato fluid through a strainer 32 to a centrifugal pump 33 which discharges the fluid by way of a pipe 34 into a closed preheater tank 35. This preheating of the fluid takes place through the medium of a coil 36 submerged in the fluid and preferably heated by exhaust steam as will be described hereinafter. The tank 35 discharges at the bottom through a valve 37 arranged in one position to communicate with a drain pipe 38 and in operating condition of the apparatus to communicate with a centrifugal pump 40. The discharge of the pump 40 delivers the preheated fluid by way of a pipe 41 to an evaporating vessel 42 similar to that described for Figure 1, except, in this instance, the heating coil 43 is only in the circulation of compressed vapor from a turbo-pump 44, which has its inlet in communication with the vapor space of the vessel 42 by a pipe 45 and its outlet to a drain trap 46. The pump 44 is driven by a steam turbine 47 supplied by a pipe 48 from a main steam pipe 50 which is connected to a source of steam supply. The vessel 42 has a discharge at the bottom by way of a valve 51 arranged in operating condition of the system to communicate with the intake of a centrifugal pump 52 and in inoperative condition of the system to communicate with a drainpipe 53. A paddle type of agitator 54 may be located within the vessel 42 and be driven by an electric motor 55.

In order to complete the evaporation of the tomato fluid, a second evaporating vessel 56 is provided into which the partially concentrated fluid is delivered by a pipe 57 from the discharge of the pump 52. The vessel 56 is of the closed type heretofore described having a heater coil 58 therein connected at one end to the discharge of a turbo-pump 60 and at the other end to a drain trap 61. The pump 60 is arranged to be driven from a steam turbine 62 receiving steam by way of a pipe 63 from the main supply pipe 50. The inlet to the pump 60 communicates with the vapor space of the vessel 56 by a pipe 64. Preferably this vessel 56 has a bottom in the form of an elongated funnel 65 arranged to discharge through a control valve 66 to a pipe 67 which delivers the evaporated pulp to a suitable container as will be understood. An agitator 68 is preferably mounted for rotation

within the body of pulp and is driven by an electric motor 70 or other power means.

For economical operation exhaust steam from the turbines 47 and 62 discharges by way of the respective pipes 71 and 72 to a conduit 73 which communicates with and supplies heat to the coil 36. Also the centrifugal pumps 33, 40 and 52 are respectively arranged to exhaust into the conduit 73, by pipes 74, 75 and 76. The main steam supply pipe 50 terminates within the decorticator 31 and functions in the scalding of the tomatoes.

In the operation of the continuous system of Fig. 2, the tomato liquid as discharged from the strainer is free from skins and seeds and enters the preheater 35 at a temperature approximately 180° F. This represents a saving at this point of at least 35 B. t. u.'s per pound. When delivered to the first evaporator 42 from the preheater 35 its temperature has risen to 200° F. or 212° F. and in this evaporator 42 the heating takes place below atmospheric pressure in order to preserve the color, flavor and to prevent the thickened pulp from being burned by the coils 43. Hence, by reason of the vacuum conditions the tomato liquid enters the second evaporator at a temperature of approximately 130° F. and since no additional steam or condensing water is necessary to operate the unit there is a large saving of B. t. u.'s which is, of course, reflected in a saving of coal as compared to other evaporating systems. This is evident because the vacuum is created by exhaust steam from the turbines and pumps.

In the system of Fig. 2 attention is directed to the novel three way valve discharge employed with each of the two evaporators 42 and 56 in that the ported valve plug 71 (Fig. 3) not only controls communication between an evaporator and the respective discharge outlets 67 and 72 but also forms a bearing for the shaft 80 of the agitator 68. A hand lever 81 serves to shift the valve plug to different control positions as will be understood.

I claim:

1. In an apparatus for evaporating tomato fluid, the combination of a plurality of evaporating kettles, conduit means interconnecting said kettles for transferring said liquid from one kettle to another in sequence relation from the bottom of one kettle to the top of the next kettle, a preheater connected to a source of tomato fluid, means for feeding said fluid from said preheater to the first kettle of said sequence, heating coils in the respective kettles, means including rotary compressors for respectively withdrawing vapors from said kettles and into the respective heating coils, an elongated steep-sided funnel in the bottom of the last sequence kettle for discharging the evaporated tomato pulp, and an agitator means mounted in said funnel.

2. In an apparatus for evaporating tomato fluid, the combination of two evaporating kettles, sealing closures for access to the respective kettles, a preheater, means for delivering tomato fluid into the top of said preheater, means including a pump for transferring said fluid from the bottom of said preheater to the top of the first of said kettles, a heating coil in said first kettle, means including a rotary compressor for drawing vapor from said first kettle and supplying it under pressure to said heating coil to increase the temperature of the surrounding vapors, means including a pump for transferring fluid from the bottom of said first kettle to the top

of the second kettle, a heating coil in said second kettle, means including a rotary compressor for drawing vapor from said second kettle and supplying it under pressure to the heating coil in said second kettle to increase the temperature of the surrounding vapors, and means to discharge the concentrated tomato pulp from said second kettle.
